Hubert R. Humphrey

UNITED STATES PATENT OFFICE.

HUBERT R. HUMPHREY, OF KALAMAZOO, MICHIGAN, ASSIGNOR TO GENERAL GAS LIGHT COMPANY, OF KALAMAZOO, MICHIGAN.

GAS HEATER.

Application filed October 25, 1922. Serial No. 596,900.

To all whom it may concern:

Be it known that I, HUBERT R. HUMPHREY, a citizen of the United States, residing at the city and county of Kalamazoo, State of Michigan, have invented certain new and useful Improvements in Gas Heaters, of which the following is a specification.

This invention relates to improvements in gas heaters.

10 The main objects of this invention are:

First, to provide an improved combined fire back and radiating element for gas heaters, which may be manufactured and handled as a unit, and which is attractive in appearance and very efficient.

Second, to provide an improved gas heater in which the fragile parts are assembled and supported so that they are not likely to be broken, and remain in operative position.

20 Further objects, and objects pertaining to details and economies of construction and operation will definitely appear from the detailed description to follow.

I accomplish the objects of my invention by the devices and means described in the following specification. The invention is clearly defined and pointed out in the claims.

30 A structure which is a preferred embodiment of my invention is clearly illustrated in the accompanying drawing forming a part of this application, in which:

Fig. I is a front perspective view of a gas heater embodying the features of my invention, the embodiment being in a portable heater.

35 Fig. II is a detail vertical section on a line corresponding to line 2—2 of Figs. I, III and IV.

Fig. III is a detail view, partially in vertical section on a line corresponding to line 3—3 of Figs. II and IV.

Fig. IV is an inverted view of my combined fireback and radiating element.

Fig. V is a front elevation of a gas heater embodying my invention installed as a wall heater.

Fig. VI is a detail vertical section on a line corresponding to line 6—6 of Figs. V and VII.

50 Fig. VII is a detail horizontal section on a line corresponding to line 7—7 of Fig. VI.

In the drawing the sectional views are taken looking in the direction of the little arrows at the ends of the section lines and

similar numerals of reference refer to similar parts throughout the several views.

Referring to the drawing, I have in Figs. I, II and III shown my improvements embodied in a portable heater of the type shown in the application of Alfred H. Humphrey, Serial No. 339,917, filed November 22, 1919, in which a base 1 is provided having an upright or standard 2 on which the body 3 of the heater is pivotally mounted at 4.

The body 3 is formed as a sheet metal stamping and comprises, back, top, bottom and side walls formed of the continuous outwarded flange 5. The burner 6 is mounted below the body and is provided with a plurality of tips 7.

70 My improved combined fireback and radiating element consists of the rear wall 8 of substantial thickness and body constituting a fire back for the heater. The reticulated front 9 is connected or formed with the back 75 wall being connected thereto through the integral bosses or tie members 10. These are preferably arranged in vertically aligned rows as illustrated, the rows being aligned so that the tips 7 of the burners discharge between them, the tips being directed through holes 12 in the bottom wall of the casing. A horizontal row of tie members 10 is arranged at the bottom thereby, in effect, providing holes.

80 The foraminated or reticulated front 9 is preferably rearwardly inclined thereby providing an upwardly tapered combustion space 13 between the front and rear walls. Spinelike projections 14 are provided on 90 the back, these projections being in the combustion chamber become incandescent and add not only to the appearance but to the efficiency of the heater.

85 The fireback and radiating element fits within the body walls, the rear wall having flanges 15 at its side edges and a flange 16 at the top.

In the embodiment shown in Figs. V, VI and VII the heater body is provided with 100 openings 17 at the top so that the product of combustion may pass through the openings 18 of the top flange 16. This embodiment is especially designed to be mounted or fitted in a recess 20 in a wall, as 21, there being a flue 22 in the wall provided with a hood 23 at the upper end of the recess. The parts are substantially the same as described

with the exception of the holes 17 in the top wall of the heater body, a bracket 24 being substituted for the base 1 to render the structure more compact and properly support it 5 within the recess.

My improved heater is very efficient and at the same time is attractive in appearance. The fragile part, or combined fire back and radiating element which is formed of earthy 10 material is supported so that it is not likely to be broken in handling, as in assembling or after assembled in the heater.

I have illustrated and described embodiments of my invention which I consider very 15 practical. I have not attempted to illustrate the various adaptations and modifications which might be desirable to adapt my improvements to various types of heaters to which they are applicable, as I believe the 20 disclosure made will enable those skilled in the art to which my invention relates to embody or adapt the same as may be desired.

Having thus described my invention what I claim as new and desire to secure by Letters 25 Patent is:

1. In a gas heater, the combination with a body member comprising back, top, bottom and side walls, the bottom and top walls having aligned openings therein, of a combined fireback and radiating element fitting within said body with its edges in contact with the walls thereof and consisting of a rear wall constituting a fireback and a foraminous front wall integrally connected to 30 said rear wall by spaced tie members disposed in vertical rows between the openings in the said top and bottom walls of said body, and a burner provided with tips aligned with said openings in said body 35 walls.

2. In a gas heater, the combination with a body member comprising back, top, bottom and side walls, of a combined fireback and radiating element fitting within said body 45 with its edges in contact with the walls thereof and consisting of a rear wall constituting a fireback and a foraminous front wall integrally connected to said rear wall by spaced tie members, and a burner provided with tips directed between said front 50 and rear walls.

3. In a gas heater, the combination with a body, of a combined fireback and radiating element consisting of a rear wall constituting a fireback and a foraminous front wall integrally connected thereto by spaced tie members disposed in vertically aligned rows,

the face of said rear wall having a plurality of projections thereon between the tie members, and a burner provided with tips directed between the rows of tie members. 55

4. In a gas heater, the combination with a body, of a combined fireback and radiating element consisting of a rear wall constituting a fireback and a foraminous front wall integrally connected thereto by spaced tie members, and a burner provided with tips directed between the rows of tie members. 65

5. In a gas heater, the combination with a body, of a combined fireback and radiating element consisting of a rear wall constituting a fireback and a foraminous front wall integrally connected thereto by spaced tie members, and a burner provided with tips directed between the front and back walls. 70

6. A combined radiating element and fireback for gas heaters comprising an imperforate rear wall of substantial thickness, and a foraminous front wall disposed in a rearwardly inclined relation relative to the rear wall, said walls being connected by spaced tie members integral therewith, the tie members being disposed in vertical rows, the rear wall having a plurality of spine-like projections. 75

7. A combined radiating element and fireback for gas heaters comprising an imperforate rear wall, and a foraminous front wall, said walls being connected by spaced tie members integral therewith and disposed in vertical rows. 80

8. A combined radiating element and fireback for gas heaters comprising a rear wall constituting a fireback, and a reticulated front wall spaced from and formed integral with said rear wall, there being a multiplicity of integral projections in the space between the walls. 85

9. A combined radiating element and fireback for gas heaters comprising a rear wall constituting a fireback, and a reticulated front wall spaced from and connected to said rear wall by integral spaced tie members. 100

10. A combined radiating element and fireback for gas heaters comprising an imperforate rear wall constituting a fireback, and a foraminous front wall disposed in spaced relation to said rear wall and connected thereto by a multiplicity of tie members, the rear wall having a multiplicity of projections in the space between the walls. 105

In witness whereof I have hereunto set my hand.

HUBERT R. HUMPHREY,
